FINISHING ROLL POLISHER

Filed Aug. 27, 1929

UNITED STATES PATENT OFFICE

DAVID H. WILLIAMS AND OWEN L. BECK, OF APOLLO, PENNSYLVANIA

FINISHING ROLL POLISHER

Application filed August 27, 1929. Serial No. 388,706.

Our invention relates to a polishing apparatus designed for removing any inequalities from the peripheries of finishing rolls of metal sheet rolling mills, to assure perfectly finished metal sheets after the finish rolling operation.

The usual method employed for polishing finishing rolls consists of securing the polishing stone adjacent to the end of a lever which is fulcrumed and manipulated by the workman so that the polishing stone is passed over and pressed against the periphery of the roll, while the latter is rotating. This method is very inefficient, renders the mill temporarily inoperative, and entails arduous labor.

Important objects of the invention are to provide a finishing roll polisher of the character described which is automatic in its 20 operation, which will function during the sheet rolling operation, which may be readily installed in a rolling mill already erected, as well as form a component part of a new rolling mill structure, which may 25 be readily removed from the rolling mill when required, or replaced to the latter, and which may be adjusted to operate on the entire periphery of the roll or any desired portion thereof.

Further objects of the invention are to provide a device of the class stated, which is simple in its construction and arrangement, strong, durable and efficient in its use, positive in its action, and comparatively inexpensive to manufacture, install, operate and maintain.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawings wherein like numerals of reference designate corresponding parts throughout the several views:—

Figure 1 is a front elevational view of a rolling mill structure embodying the present invention.

Figure 2 is an enlarged side view of the shifter member, and of associated parts.

Figure 3 is an enlarged side view of the polisher saddle carrying the polishing stones.

Figure 4 is an enlarged side view of the suspension arms and of associated parts.

Figure 5 is an enlarged view, partly in cross section, of the slide bearing and its supporting shaft.

Referring in detail to the drawings 1 denotes the stand or frame of a rolling mill structure, in which a pair of associated rolls, indicated at 2 and 3, are revolubly mounted. The rolls 2 and 3 are disposed horizontally with the former above the latter, and together with the frame 1, are of a construction and operation now commonly employed in rolling mill practice.

The drawings and description illustrate and describe the adaptation of the present invention to the front of the rolling mill structure and as applied to the top roll 2 only. It being obvious that the lower roll 3 is also equipped with an identically constructed polishing apparatus disposed at the rear of the rolling mill structure.

Our improved polishing apparatus comprises a horizontally disposed, tubular feed screw 4, which is journaled for rotation and removal in the frame 1. The feed screw 4 is disposed above but adjacent to the horizontal plane of the under side of the top roll 2, and extends parallel to the latter. One end of the feed screw is squared to provide a connecting end 5, which projects from the adjacent side of the frame 1.

The feed screw 4 is driven by an electric motor 6, which is suitably supported on a bracket 7 fixed to the frame 1. The motor 6 is provided with a worm 8, which meshes with a worm wheel 9. The latter is journaled for rotation in a suitable bearing 10 supported on the bracket 7. The hub 11, of the worm wheel 9 is formed with a square socket 12, which is adapted for the reception of the squared connecting end 5, of the

feed screw 4. The operation of the motor 6, through its connection with the feed screw 4, in the manner stated, will impart rotation to the latter.

- 5 The feed screw 4 is maintained in its position in the frame 1, by a releasable collar 13, which abuts against the inner side of the frame 1. The collar 13 prevents the longitudinal movement of the feed screw 10 4, in one direction, and the engagement of the square connecting end 5 in the hub socket 12 prevents its movement in the other direction.

The feed screw 4 is tubular permitting 15 of the circulation of water therethrough to prevent overheating of the feed screw 4 due to its proximity to the roll 2. A water supply element 14 connects with one end of the feed screw 4, and the water passes from 20 the latter through apertures 15, which are formed in the projecting, squared connecting end 5 thereof.

- A shifter member 16 is mounted on the feed screw 4 and engages a slide bearing 17. 25 The shifter member 16 comprises a hinged, internally threaded, bearing 18, which threadedly engages the feed screw 4, and is provided with latching elements 19 to permit and facilitate its removal from the feed screw 4 or its replacement thereon. The shifter member 16 further includes a rearwardly projecting yoke 20 which engages the center portion 21 of the slide bearing 17. The latter is also formed to provide 35 end portions 22 and 23, which together with the center portion 21, are divided from each other by respective annular flanges 24.

The slide bearing 17 is slidably mounted 40 on a tubular supporting shaft 25. The latter extends parallel to the feed screw 4, but is disposed rearwardly of and above the latter. The ends of the supporting shaft 25 are removably mounted in the bearing slots 26, which are formed in the free front ends 45 of respective suspension arms 27. The top ends of the bearing slots 26 are open and are covered by plates 28 to maintain respective ends of the supporting shaft 25 in said bearing slots 26. One end of each of the 50 plates 28 is pivotally connected, as at 29, to the top of respective suspension arms 27. The other end of the plate 28 is formed with an open slot 30, which engages a bolt 31 55 threadedly mounted in the top of suspension arms 27. The partial release of the bolts 31 will allow the plates 28 to be swung on their pivotal connections 29 and permit the removal of the supporting shaft 25 from 60 the bearing slots 26 in the suspension arms 27.

The rear ends of the suspension arms 27 are pivotally connected by bolts 27' to the frame 1 to dispose the former at respective 65 ends of the top roll 2. The suspension arms

27 are curved longitudinally to conform to the curvature of the top roll 2.

The supporting shaft 25 is hollow to allow the circulation of water therethrough to prevent overheating due to its proximity to the top roll 2. The tubular supporting shaft 25 is formed with closed ends, and is provided with a water inlet connection 32 and a water outlet connection 33. The inlet and outlet connections 32 and 33 are disposed adjacent to the ends of the supporting shaft 25.

A saddle 34, formed with an open bearing groove 34' on its outer side, is carried by each of the end portions 22 and 23, of the slide bearing 17, at respective sides of the shifter member 16. The end portions 22 and 23 are mounted in the bearing grooves 34' of respective saddles 34, and the latter may be readily removed or replaced by elevating the supporting shaft 25, in a manner permitted by the latter's connection with the suspension arms 27, to provide clearance between the supporting shaft 25 and the top roll 2.

Each of the saddles 34 carries a pair of horizontally extending, parallel disposed, polishing stones 35 which are of a type now commonly employed for polishing sheet mill rolls. Each of the saddles 34 is formed on its inner side with a pair of grooves 36 for the reception of the polishing stones 35. The latter have tapering sides and the side walls of the grooves 36 are correspondingly tapered to maintain the polishing stones 35 in said grooves 36, and to permit of and facilitate the removal and replacement of the polishing stones 35 when required.

Each of the saddles 34 is positioned rearwardly of the slide bearing 17, and both of the polishing stones 35, carried thereby, frictionally engage the periphery of the top roll 2, one of the polishing stones 35 being disposed above the slide bearing 17 and the other below the latter.

As it is necessary for the polishing stones 35 to operate under great pressure to effect the polishing operation, air pressure is provided through a pair of vertically disposed air cylinders 37. An air cylinder 37 is fixed at each side of the frame 1, and includes a piston and a piston rod 38, which has its lower end pivotally connected, as at 39, adjacent to the front free end of respective suspension arms 27.

The cylinders 37 are joined with suitable air supply and control elements for projecting the piston rods 38 to exert pressure upon the polishing stones 35 during the roll polishing operation, and for withdrawing the piston rods 38 to release the pressure from the polishing stones 35 and to elevate the respective suspension arms 27 when desired. The rear ends of the suspension arms 27 are provided with elongated slots 40 for

the passage of the pivoting bolts 27', to allow necessary compensatory movements of the suspension arms 27 while the piston rods 38 shift vertically from and into the fixed cylinders 37.

As the hinged bearing 18 of the shifter member 16 threadedly engages the feed screw 4, the shifter member 16 will travel along the feed screw 4 in either direction depending on the direction of rotation of the feed screw 4. The travel of the shifter member 16, will, of course, slide the slide bearing 17 in the same direction along the supporting shaft 25. The saddles 34 with the polishing stones 35, being carried by the slide bearing 17, will likewise shift with the latter.

The motor 6 is of a reversible type, now in common use, and is controlled by the functions of a reversing switch 41, which is fixed to the frame 1 and operated by a depending switch lever 42. The lower end of the latter is formed to provide a fork 43 which straddles a flat, horizontally disposed operating bar 44.

The operating bar 44 extends parallel to the top roll 2 and is mounted for longitudinal movement in apertures 45 provided in respective sides of the frame 1. A detachable leg 46 depends from the center of the bar 44, and the lower end thereof is loosely engaged between a pair of ears 47 formed on the top of the yoke 20, of the shifter member 16. The horizontal movement of the latter during the polishing operation will impart like horizontal movement to the operating bar 44. The loose engagement of the leg 46 in the ears 47, will permit the necessary vacillation of the shifter member 16 during the polishing operation, without interference with or imparting such vacillatory movement to the operating bar 44.

A pair of removable actuating lugs 48, are fixed in spaced relation on the top edge of the operating bar 44. The latter is formed with a plurality of apertures 49 permitting the spacing adjustment of the actuating lugs 48.

The operating bar 44 passes through the forked lower end 43 of the switch lever 42, and the actuating lugs 48 are disposed on respective sides thereof. The purpose of the actuating lugs 48 is to engage and shift the switch lever 42 in both directions to operate the switch 41, which controls the direction of rotation of the motor 6.

The relative positions of the actuating lugs 48 on the operating bar 44, is such that one of the lugs 48 will engage and shift the switch lever 42 to reverse the operation of the motor 6 when the polishing devices on the slide shaft 17 have reached a desired distance to one side of the roll 2, while the other lug will shift the lever 42 in the other

direction to reverse the rotation of the motor 6 when the polishing devices have reached the desired distance to the other side of the roll 2.

In our improved polishing apparatus, the shifter element 16, saddles 34 with polishing stones 35, slide bearing 17, and the operating bar 44, will shift constantly back and forth as long as the motor 6 is operating. The operation is entirely automatic and is performed during the sheet rolling operation. Such continuous polishing operation will maintain the roll in perfect condition for rolling operations, and the latter need not be suspended to permit the polishing operation.

It will here be noted that all parts of the invention are readily removable from the rolling mill, thereby permitting access to the rolls when heating, repairing or changing the latter.

The present invention provides a most efficient device of its kind, which will operate automatically for maintaining the rolls in perfect condition at all times.

What we claim is:

In combination, a roll polisher, of the character described, comprising a revolvably mounted tubular feed screw, a removably mounted tubular supporting shaft extending parallel to said feed screw, a slide bearing being longitudinally shiftable on said supporting shaft, a shifter member including a hinged bearing threadedly engaging said feed screw, said shifter member further including a yoke engaging said slide bearing, a removable saddle carried at each end of said slide bearing, a pair of polishing members removably mounted in each of said saddles, suspension arms for said supporting shaft, air operated elements connecting with said suspension arms for imparting pressure to said polishing members, said feed screw and said supporting shaft being provided with inlets and outlets to permit of the passage of a cooling medium through same.

In testimony whereof we affix our signatures.

DAVID H. WILLIAMS.
